INVENTOR

BY Victor J. Evans

ATTORNEY

WITNESS: Clara E. Woodworth

UNITED STATES PATENT OFFICE.

GEORGE E. THORBERG, OF MANDAN, NORTH DAKOTA.

BELT LOOP.

Application filed July 21, 1923. Serial No. 653,055.

This invention relates to a belt loop structure designed for attachment to men's trousers, and an object of the invention is to provide a belt loop which may be quickly and easily attached to trousers at the waistband thereof for engaging a belt and supporting the trousers therefrom.

Another object of this invention is to provide a belt loop structure as specified which comprises a metallic hook or loop and an attaching pad of rubber or analogous material which latter pad is placed against the inner surface of the waistband of the trousers and will serve the dual function of attaching the belt loop to the trousers in such manner as to prevent tearing of the cloth and will also prevent, to a material extent, the shirt of the wearer from "creeping up."

Other objects of the invention will appear in the following detailed description taken in connection with the accompanying drawing wherein:—

Fig. 1 is a front elevation of the improved belt loop showing it in use.

Fig. 2 is an inner or rear elevation of the belt loop showing it in use.

Fig. 3 is a vertical section through the belt loop taken on the line 3—3 of Fig. 1.

Fig. 4 is a section on the line 4—4 of Fig. 1.

Fig. 5 is a plan view of the blank from which the belt loop is formed.

Fig. 6 is a front elevation of a modified form of the belt loop.

Fig. 7 is a cross section on the line 7—7 of Fig. 6.

Referring more particularly to the drawings, the improved belt loop comprises a body plate 1 which is rectangular in shape and is formed of any suitable type of sheet metal. The rectangular body 1 has a tongue 2 projecting from one end edge thereof, which in use, is bent outwardly and downwardly over the body, as shown clearly in Figs. 3 and 4 of the drawings, for frictionally engaging over a belt as indicated at 3. The body plate 1 has piercing and attaching tongues 4 formed on its end edges and a pair of piercing attaching tongues 5 formed on its side edge opposite from which the tongue 2 projects. The outer ends of the tongues 4 and 5 are tapered to provide pierc-

ing points, and the tongues are provided with cut out portions 6 in their edges to weaken them so as to permit them to be bent transversely to lie flat against the inner surface of the elastic attaching pad 7. The elastic attaching pad 7 is preferably, formed of rubber or analogous material and it is placed against the inner surface of the trousers A, inwardly of the metal body plate 1. The tip of the tongues 4 and 5 are bent inwardly and embedded in the resilient attaching pad 7, as clearly shown at 8 in Fig. 4 of the drawings, so as to prevent them from tearing the fabric of which the trousers are made and also to eliminate liability of their pricking the fingers of the wearer.

By particular reference to Figs. 2, 4 and 5 of the drawings it will be noted that the tongues 4 extend into the pad 7 transversely to the manner in which the tongues 5 enter the pad and that they are bent across the pad in a transverse direction to that in which the tongues 5 are bent across the pad thereby providing secure connection between the pad and the plate 1 so as to securely hold the plate in proper attached position to the fabric A.

In Figs. 6 and 7 of the drawings, a slight modification of the invention is shown, in which the plate 1', is provided with a plurality of openings 5' which receive therethrough thread 10 for stitching the plate 1' and pad 7' to the trousers as shown at B. If it is so desired the plate 1' may be inserted between two layers of the fabric C, as clearly shown in Fig. 7 of the drawings. The tongue 2' is formed upon the plate 1' in the same manner in which the tongue 2 is provided.

It is, of course, to be understood that the invention may be constructed in other manners and the parts associated in different relations and, therefore, I do not desire to be limited in any manner except as set forth in the claim hereunto appended.

Having thus described my invention what I claim is:—

A device for detachably connecting a belt to a pair of trousers including a substantially rectangularly shaped body, a tongue at one side of the body and bent to a position transversely of the body to define a hook

for receiving a portion of the belt, attaching tongues formed as an integral part of the body and adapted to penetrate through the waist band of the trousers, and an elastic member disposed on the inner side of the waist band, said attaching tongues extending through the elastic member and defining

end portions bent upon and embedded in the elastic member, said elastic member cooperating with the attaching tongues for connecting the body to the waist band. 10

In testimony whereof I affix my signature.

GEO. E. THORBERG.
